UNITED STATES PATENT OFFICE.

PAUL W. WIGGERT, OF IDAGROVE, IOWA.

ELECTRICAL SWITCH-LOCK.

1,249,872.

Specification of Letters Patent. Patented Dec. 11, 1917.

Application filed July 10, 1916. Serial No. 108,411.

To all whom it may concern:

Be it known that I, PAUL W. WIGGERT, a citizen of the United States, residing at Idagrove, in the county of Ida and State of Iowa, have invented certain new and useful Improvements in Electrical Switch-Locks, of which the following is a specification.

This invention relates to certain new and useful improvements in electrical switch locks.

The primary object of this invention resides in the provision of an electrical switch lock which will be of improved construction as well as cheap to manufacture.

Another object of the invention resides in the provision of a switch lock of this character which will be composed of a minimum number of parts, and in which the rotary members may be readily moved to inoperative position to prevent the switch from being closed except by a party familiar with the combination.

The invention has for a further object the provision of a switch lock of this character which will be of such construction that the rotary members may readily be adjusted with respect to one another to form various combinations.

With these general objects in view and others that will appear as the nature of the invention is better understood, the same consists in the novel combination and arrangement of parts hereinafter more fully described, illustrated in the accompanying drawings, and pointed out in the appended claims.

In the drawings forming a part of this application and in which like-designating characters refer to corresponding parts throughout the several views:

Figure 1 is a plan view of the improved form of electrical switch lock with the casing in section.

Fig. 2 is a detail section substantially on the plane of line 2—2 of Fig. 1.

Fig. 3 is a plan view of the complete device with the parts reduced in size.

Fig. 4 is a plan of the lower rotary member, and Fig. 5 is a fragmentary plan view showing the guide slot with the shank of the slidable spring operating member engaged therein.

Fig. 6 is a detail sectional view on the line 6—6 of Fig. 1.

Referring more in detail to the drawing, 55 1 designates a casing of conventional form, within which is positioned a post 2 having a lower rotary member 3 and an upper rotary member 4 mounted thereon, said members 3 and 4 having inwardly directed radial slots 60 5 formed therein and adapted to register at times. The lower rotary member 3 has an arcuate concentric groove 6 formed in its upper face to receive the point of the operating screw 7 which may be secured in any one of 65 the openings 8 arranged concentric in the upper rotary member 4 as will be readily understood by referring to Figs. 1 and 2 of the drawings. The lower disk 3 is loosely mounted upon the post 2 and normally held against 70 rotation by means of a curved leaf spring 9, engaged with the periphery thereof and mounted upon a suitable post 10 positioned in the case 1. The upper disk 4 is keyed to the post 2, as shown at 11 and said post 2 is 75 prevented from being withdrawn from the case 1 by means of a collar 12 engaged around the same between the upper rotary member 4 and the top of the casing 1. The post 2 extends through the top of the casing 80 1 and has a suitable head 13 formed thereon and a pointer 14 projecting laterally from the same adjacent said head 13. The pointer 14 is adapted to ride over the dial 15 provided upon the outer face of the case 1 to 85 indicate the position of the rotary members 3 and 4. It will be readily seen that by changing the position of the screw 7 in the rotary member 4, the combination will be changed, owing to the fact that the screw 7 90 must travel around the groove 6 and connect the end walls of the latter to rotate the lower rotary member 3.

When the post 2 has been properly operated to bring the rotary member 3 to the 95 proper position and the upper rotary member 4 to such position upon the same that the two slots 5 will register, the slidable member 16 may be moved within the casing 1 to force the reduced end 17 thereof into the 100 registering slots 5, said slidable member 16 having a shank or standard 18 extending from its upper face and projecting through the elongated slot 19 in the top of the casing 1. This shank or standard 18 is preferably 105 squared in cross section to prevent turning of the slidable spring operating member 16. The member 16 has an enlargement 20

formed upon one side to normally engage with the seat 21 formed for the same in the resilient circuit closer 22 by bending the latter adjacent the post 23 around which one end of the circuit closer 22 is secured. The circuit closer 22 is then curved for engagement with the slidable member 16, as shown at 24 and then provided with a second seat 25. The free end of this member 22 is curved so that when the slidable member 16 is moved to operative position with the end 17 thereof engaged in the registering slots 5, said free end of the member 22 will be forced into engagement with the switch post 26 to complete the circuit from said switch post 26 and the post 23. As soon as the slidable member 16 is in this position, the enlargement 20 will be pressed against the curved portion 24 of the circuit closer 22 or engaged 15 in the seat 25, thereby holding this circuit closer in contact with the switch post 26. As soon as the slidable member 16 is withdrawn however, the portion 24 of the circuit closer will engage with the side of the member 16 20 and the free end thereof moved away from the switch post 26, thereby breaking the circuit. Upon a slight turn of the post 2 in either direction, at least one of the slots 5 will be moved away from the ends 17 of the 25 member 16 and thereby make it practically impossible for any party not familiar with the combination to again close the circuit.

Pivotedly mounted upon the upper end of the binding post 26, is the switch lever 27 which may be engaged with any one of a plurality of binding posts 28 having wires 29 engaged therewith. Another wire 30 is connected with the post 23 and the wire 30 and wires 29 may be connected in any suitable well-known manner to the opposite poles of a battery or the like.

The member 16 has a dove-tailed lower portion 16' which is slidably engaged in the dove-tailed channel member 31 mounted 45 upon the bottom of the casing 1, as clearly shown in Fig. 6 of the drawings. This will serve to properly guide the member 16 and prevent upward movement of the same. It will be understood, however, that the upper 50 dove tailed portion 16' is only opposite the main or body portion of the member 16 and is connected to the same by a neck portion 32.

From the foregoing, it will be apparent 55 that I have provided an improved form of electrical switch lock which may be readily operated by an authorized party to complete any one or a number of circuits, but which is of such construction and operation as to 60 make it practically impossible for an unauthorized person to close the switch.

While the form of the invention herein shown and described is what is believed to be the preferred embodiment thereof, it is 65 nevertheless to be understood that minor

changes may be made therein without departing from the spirit and scope of the invention as claimed.

What I claim as new is:—

1. An electrical switch lock comprising a post, a rotary member loosely mounted upon said post, means for resiliently retaining said rotary member in normal position, a second rotary member keyed to said post, adjustable connections between said rotary members, means for indicating the position of said first rotary member, said rotary members having slots adapted to register with one another, a slidable member adapted to be forced into said slots when in proper registering position, a switch post, a binding post, and a spring mounted upon said binding post and adapted to be forced into engagement with said switch post upon movement of said slidable member into said slots.

2. An electrical switch lock comprising a casing, a rotary member mounted therein, a second rotary member loosely mounted within the casing and adapted to be held in normal position, adjustable loose connections between said rotary members, a resilient circuit closing member, a slidable member normally held against movement by the circuit closing member, said rotary members being adapted to receive said slidable member at times, said slidable member being adapted to move said circuit closing member to operative position when received by said rotary members, and means for indicating the position of said rotary members.

3. An electrical switch lock comprising a casing, a post rotatably mounted in said casing, rotary members mounted upon said post, one of said members being adapted to rotate with said post, means adjustable in said last-mentioned member to rotate the remaining member at times, means for resiliently retaining the last-mentioned rotary member in normal position, said rotary members being provided with peripheral slots adapted to register at times, a resilient circuit closing member, a slidable member engaged with the circuit closer and retained against accidental movement thereby and adapted to operate said circuit closing member, a stationary contact for co-operation with the circuit closer, said slidable member being adapted to enter said slots when the latter are in registering position, and the last rotary member is in normal position, and means to indicate the position of said rotary members.

4. An electrical switch lock comprising rotary slotted members, one of said members being normally stationary, a supporting post for said rotary members, the slots of said rotary members being adapted to register, a slidable member adapted to enter the registering slots, a binding post, a

spring carried by said binding post, a switch post, and an enlargement formed on said 5
slidable member and engaged with said
spring to force the latter into engagement
with said switch post as said slidable mem-
ber enters said slots and form electrical
connections between said switch post and
said binding post, a plurality of binding
posts, a switch lever carried by said switch
10 post and adapted for engagement with
either of the last-mentioned binding posts,
and means to indicate the position of said
rotary members.

5. An electrical switch lock comprising a
15 rotary member having a peripheral slot, a
concentric arcuate groove in one face, a sec-
ond rotary member positioned upon the
first-mentioned rotary member and provided
20 with a plurality of concentrically-arranged
openings, a member removably positioned
in one of said openings and engaged in said
groove, to rotate the first-mentioned rotary
member, said second mentioned rotary mem-
25 ber being provided with a peripheral slot
adapted to register with the peripheral slot
of the first-mentioned rotary member, a sup-
porting post for said rotary members, means
for indicating when the slots in the disks are
30 in registration, a resilient circuit closing
member, and a slidable member adapted to
enter said slots and operate said circuit clos-
ing member, the circuit closing member
serving to retain the slidable member against
35 accidental movement.

35 6. An electric switch comprising a casing,
a plurality of disks rotatably mounted there-
in and provided with peripheral slots, means
for rotating the disks to bring the slots into
40 registration, a stationary contact mounted
in the casing, a movable contact also mount-
ed in the casing, and a slidable member
having operative engagement with the mov-
able contact and adapted to be projected
45 into the registering slots, the movable con-
tact co-operating with the stationary con-
tact to close an electrical circuit and always
retaining the slidable member against acci-
dental movement.

7. An electric switch comprising a casing,
50 a plurality of disks rotatably mounted there-
in and provided with peripheral slots, means
for rotating the disks to bring the slots into

registration, a stationary contact mounted
in the casing, a resilient contact also mount-
ed in the casing, and a slidable member hav-
ing operative engagement with the resilient
55 contact and adapted to be projected into the
registering slots, the resilient contact co-
operating with the stationary contact to
close an electrical circuit and always retain-
ing the slidable member against accidental
60 movement.

8. An electric switch lock comprising a
casing, a disk fixed to rotate within the cas-
ing and provided with an annular groove 65
which is interrupted intermediate its ends
and further provided with a slot, a second
disk also rotatable in the casing and pro-
vided with a plurality of openings and a
slot, a pin extending through one of the 70
openings and movable in the annular groove
and adapted to contact with the end walls
thereof to rotate the first mentioned disk,
a stationary contact in the casing, a movable
75 contact also in the casing, and a slidable
member adapted to be projected into the
slots in the disks upon registration of the
same and to move the movable contact into
engagement with the stationary contact
80 upon such movement, said movable contact
serving to hold said slidable block against
accidental displacement.

9. An electric switch comprising a casing
having a longitudinal slot in one wall there-
of, a plurality of disks rotatably mounted in 85
the casing provided with slots adapted for
registration, means operated exteriorly of
the casing for bringing the slots into regis-
tration, stationary and movable contact
mounted in the casings, a slidable bolt also 90
mounted in the casing and adapted to be
projected into the registering slots, and
for actuating the movable contact, said mov-
able contact serving to hold said slidable
block against accidental displacement, and 95
an operating member carried by the slid-
able member movable in the longitudinal
slot.

In testimony whereof I affix my signature
in presence of two witnesses.
